ABSTRACT: Device for crucible-free zone melting a crystalline rod, particularly a semiconductor rod, includes two induction heating coils annularly surrounding the crystalline rod, and driving means for adjusting the position of the induction heating coils relative to one another in a direction transverse to the rod axis. Method of using the device includes relatively moving the induction heating coils away from one another transversely to the rod axis at the junction of a seed crystal with one end of the rod so as to fuse the seed crystal to the rod, relatively moving the induction heating coils on the one hand and the rod on the other hand along the axis of the rod and simultaneously relatively displacing the induction heating coils gradually toward one another in a direction transverse to the rod axis in conformity with an outwardly flaring conical portion of the rod extending from the seed crystal, until the induction heating coils substantially coaxially surround the main cylindrical portion of the rod.

**ADJUSTABLE HEATING DEVICE FOR CRUCIBLE-FREE
ZONE MELTING A CRYSTALLINE ROD**

My invention relates to device and method for crucible-free floating-zone melting a crystalline rod, particularly a semiconductor rod, wherein two induction heating coils annularly surround the crystalline rod.

It is, of course, known to fuse a seed crystal to the end of a semiconductor rod in a crucible-free floating-zone melting operation, wherein the cross section of the seed crystal is considerably smaller than that of the rod being processed. It has been found that such a difference in cross section can improve the quality of the monocrystal being formed, particularly with regard to the dislocation density thereof. After the seed crystal has been fused to the semiconductor rod, a melting zone is passed through the entire semiconductor rod. To fuse the seed crystal and the crystalline rod and to subsequently zone-melt the crystalline rod, a device has been heretofore employed, wherein two induction heating coils annularly surround the crystalline rod and the seed crystal respectively. Both induction heating coils have different dimensions, the inner diameter of one of the induction heating coils being accommodated to the thickness of the seed crystal and the inner diameter of the other heating coil being accommodated to the thickness of the crystalline rod being processed. A firm coupling is thereby attained between both induction heating coils and the respective rod portions (note German Patent 1 224 273).

In spite of these desirable coupling conditions when fusing the seed crystal to the crystalline rod and when zone-melting the crystalline rod, difficulties that were heretofore encountered in the art nevertheless still arise with regard to the coupling when a conical transition zone of the crystalline rod between the seed crystal and the cylindrical portion of the rod is being melted or when a crystalline rod having a supply rod portion differing in diameter from that of the monocrystalline semiconductor rod portion being produced is zone-melted.

It is accordingly an object of my invention to provide a device and method for crucible-free zone melting a crystalline rod, particularly a semiconductor rod, which avoids the foregoing disadvantages of the heretofore known devices and methods of this general type. More particularly, it is an object of my invention to provide such method and device which will provide good coupling between the two induction heating coils when fusing a conical transition zone between a seed crystal and the cylindrical portion of the semiconductor rod being treated.

It is a further object of my invention to provide optimum use of available high-frequency energy in all phases of the zone-melting process, that is when fusing a thin seed crystal to a thick supply rod and, as a melting zone is being passed through the rod, along a conically outwardly flaring transition between a thin seed crystal and the cylindrical portion of the thicker crystalline rod or along a transition zone from a thinner seed crystal to a thicker rod portion recrystallizing from the melting zone, while at the same time always maintaining the melting zone relatively short in the direction of travel through the rod so that it is in stable condition.

With the foregoing and other objects in view, I provide, in accordance with the invention, a device of the aforementioned type, wherein both induction heating coils are adjustably movable relative to one another by a driving mechanism in a direction transverse to the axis of the rod.

I also provide in accordance with the invention, method which includes relatively moving the two induction heating coils toward one another transversely to the rod axis at the junction of a seed crystal with one end of the rod as to fuse the seed crystal to the rod, relatively moving the coils, on the one hand, and the rod, on the other hand, along the axis of the rod and simultaneously relatively displacing the induction heating coils gradually toward one another in a direction transverse to the rod axis in conformity with an outwardly flaring conical portion of the rod extending from the seed crystal, until both coils substantially coaxially surround the main cylindrical portion of the rod.

Other features which are considered as characteristic for the invention are set forth in the appended claims.

Although the invention is illustrated and described herein as device and method for crucible-free zone melting a crystalline rod, particularly a semiconductor rod, it is nevertheless not intended to be limited to the details shown, since various modifications may be made therein without departing from the spirit of the invention and within the scope and range of equivalence of the claims.

The present invention, however, together with additional objects and advantages thereof will be best understood from the following description when read in connection with the accompanying drawings, wherein:

FIG. 1 is a perspective view of a device according to the invention having two induction heating coils adjustably displaceable relative to one another in a direction transverse to a crystalline rod being processed;

FIG. 2 is a side elevational view of the primary functional components of the device shown in FIG. 1;

FIG. 3 is a plan view of the heating coils of the device in a position wherein a thin seed crystal is being fused to a thicker crystalline rod; and

FIG. 4 is a plan view corresponding to that of FIG. 3 but showing the coils in another phase of the method, wherein the cylindrical portion of the crystalline rod is being zone-melted.

Referring now to the drawings and first particularly to FIG. 1 thereof, there are shown two induction heating coils 1 and 2 having respectively a single winding. Both induction heating coil windings are firmly coupled to one another coaxially at a common axis by a pivot 3. The mutual spacing of the windings 1 and 2 in the axial direction of their pivot 3 is, for example, about 1 mm.

The induction heating coils 1 and 2 can be connected electrically either in series or in parallel. For the use at hand, the series connection is more advantageous because, for a given stray inductance of the leads, the effective inductance of the coil is increased. Moreover, the series connection of both induction heating coils 1 and 2 provides the further advantage that only a single terminal or connection is sufficient for supplying and discharging a coolant through the heating coils which are generally tubular in form. The leads of the induction heating coils 1 and 2 are identified by reference characters 1a and 1b, on the one hand, and 2a and 2b, on the other hand, and are secured, for example by hard soldering, to bushings or sleeves 4a and 4b, on the one hand, and 5a and 5b, on the other hand. The bushings 4a, 4b and 5a, 5b consist of material of relatively good electrical conductivity such as silver, for example, and are supported on a common pivot 3 located outside the induction heating coils 1 and 2. The pivot 3 is formed of insulating material such as ceramic or a heat-resistant plastic material, for example. Each pair of bushings 4a and 4b, on the one hand, and 5a, 5b, on the other hand, is mounted so that it is turnable or twistable relative to the other by means of

40 a drive mechanism 8 through 10. The common drive mechanism for the bushings 4a, 4b, 5a, 5b is an assembly of a bevel gear 10 and two bevel gear segments 8 and 9 which are respectively secured to the bushings 4b and 5a, the bevel gear segments 8 and 9 being in meshing engagement with the bevel gear 10. The components 8 to 10 of the gear train can consist of a nonferromagnetic material such as glass, for example, or a heat-resistant plastic material, such as

45 polytetrafluoroethylene, known by the trade name Teflon, for example. Flexible connecting leads 7 serve for guiding coolant through the induction heating coils 1 and 2. The insulating pivot 3 is mounted in a frame-shaped housing 6. Between the bushings 4a and 4b, on the one hand, and 5a and 5b, on the other hand, there is provided respectively an insulating ring 14 which electrically insulates the leads 1a and 1b from one another, on the one hand, and 2a and 2b from one another, on the other hand, of both induction heating coils 1 and 2. A drive shaft 11 serves for pivoting both induction heating coils 1 and 2, the shaft 11 actuating the gear train 8 through 10 by means of a nonillustrated reversible motor.

The aforescribed device operates as follows:

When a seed crystal 12 is fused to a crystalline rod 13, as shown in FIG. 3, for example, both induction heating coils 1 and 2 are displaced toward one another about the common pivot 3, for example, by actuating the drive shaft 11 in a clockwise direction, as viewed from the right-hand side of FIG. 1 so that the seed crystal 12 is firmly coupled with the portions of the windings of the induction heating coils 1 and 2 which form an oval or somewhat lens-shaped interspace (FIG. 3). After the fusion and melting of the seed crystal 12, the induction heating coils 1 and 2 are held stationary while the crystalline rod 13 is displaced axially toward the induction heating coils 1 and 2. Thereby, for a gradual conical transition between the seed crystal 12 and the cylindrical portion of the crystalline rod 13, as shown in FIG. 2, both induction heating coils 1 and 2 are returned to an initial position in which they are coaxial to one another and to the rod 13 as shown in FIG. 4. This is effected by actuating the drive shaft 11 in the opposite rotary direction than aforescribed, namely in the counterclockwise direction as viewed from the right-hand side of FIG. 1.

The device of my invention is marked particularly by the fact that the induction heating coils 1 and 2 need not be exchanged or replaced for different diameters of the seed crystal 12 and/or for a transition of varying diameter located between the seed crystal 12 and the cylindrical portion of the crystalline rod 13.

It is also essential that during the entire zone-melting operation, both induction heating coils 1 and 2 be energized by high-frequency electric current. Thereby, the growth conditions in the crystalline rod 13 are not varied erratically and, consequently, the danger of the formation of dislocations is considerably reduced.

It is obvious that details of the aforescribed and illustrated embodiment can be varied without deviating from the basic scope and concept of the invention. Thus, for example, both induction heating coils 1 and 2 can be secured to separate pivots. The induction heating coils 1 and 2 can also be displaced in opposite directions to one another. The device of my invention is also suitable particularly for producing dislocation-free semiconductor rods, for example of silicon, having relatively large diameters. In a method carried out by such a device, after the seed crystal 12 has been fused to the crystalline rod 13, a bottleneck-shaped constriction of about 2

mm. thickness and 20 to 25 mm. length is produced by moving the nonillustrated end holders of the rod away from one another. Also, for producing this bottleneck-shaped constriction, the coupling between the induction heating coils 1 and 2, on the one hand, and this portion of the crystalline rod can be optimally adjusted.

As has previously been mentioned, the device of my invention can also be employed with good results for zone melting crystalline rods whose thickness varies over the length thereof. 10 In such a case, both induction heating coils 1 and 2 can always be adjusted to the optimum coupling between crystalline rod and the induction heating coil by displacement of the coils relative to one another in a direction transverse to the axis of the crystalline rod. A short and stable melting zone is thereby 15 obtained during the entire zone-melting operation.

I claim:

1. In a device for crucible-free zone melting a crystalline rod, a pair of induction heating coils annularly surrounding the crystalline rod, driving means for adjusting the position of 20 the induction heating coils relative to one another in a direction transverse to the axis of the crystalline rod, said induction heating coils being pivotable about a common axis located outside of said coils and extending substantially parallel to the axes of said coils and including drive means operatively connected in common to said induction heating coils for pivoting said coils about said common pivot axis.
2. Device according to claim 1 including a pivot pin having an axis coextensive with said common pivot axis, a plurality of bushings coaxially mounted on said pivot pin and turnable thereabout, said induction heating coils having a pair of leads, respectively, each of said leads being connected to a respective one of said bushings, said drive means comprising a gear transmission operatively connected to said bushings for turning said bushings and the coils connected thereto about said 35 pivot pin.
3. Device according to claim 2 wherein said gear transmission comprises a pair of bevel gear segments, secured respectively to one of the bushings connected to the respective induction heating coils, and a bevel gear meshing with both of 40 said gear segments.

4. Device according to claim 3 wherein said drive means includes a driven shaft, said bevel gear being mounted on said shaft and being rotatable thereby.
